ATTORNEY.

UNITED STATES PATENT OFFICE.

ROBERT C. GIBBS, OF EAST PROVIDENCE, AND JOSEPH ATKINSON, OF CRANSTON, RHODE ISLAND, ASSIGNORS TO CLARK AND COOMBS COMPANY, A CORPORATION OF RHODE ISLAND.

METHOD OF MAKING ORNAMENTAL BODIES OF EAR-RINGS.

1,324,807.

Specification of Letters Patent.

Patented Dec. 16, 1919.

Application filed November 30, 1918. Serial No. 264,876.

To all whom it may concern:

Be it known that we, ROBERT C. GIBBS and JOSEPH ATKINSON, both citizens of the United States, residing, respectively, at East 5 Providence and Cranston, in the county of Providence and State of Rhode Island, have invented certain new and useful Improvements in Methods of Making Ornamental Bodies of Ear-Rings, of which the following 10 is a specification.

Our invention relates to the manufacture of earring bodies, and particularly to such bodies as are crescent shaped in elevation.

Heretofore it has been regarded as necessary to stamp up two separate crescent shaped plated shells, and then solder them together at their edges, thereby leaving seams on the inner and outer peripheries, which required a replating of the article to 20 temporarily cover; and through which acids of the finishing solutions finally percolated and discolored the plating. By old methods also the ends of the bodies had to be left unclosed so that there was admitted through 25 such openings the objectionable liquid solutions.

Such methods also involved the discoloration due to soldering heat, and involved labor expense.

30 The essential object of our invention is to overcome the above enumerated disadvantages.

The invention consists in such steps and such sequence of steps as form the subject 35 matter of the appended claims.

In the accompanying drawings which form a part of this specification, and in which like reference characters indicate like parts throughout the views,

40 Figure 1 is a side elevation of the preliminarily assembled parts of the new body, Fig. 2, a longitudinal section of the same after swaging,

Fig. 3, a side elevation after trimming,

45 Fig. 4, a side elevation partly in longitudinal section, of the same after the bending operation and the insertion of the rod,

Fig. 5, a like elevation after shortening the rod, and

50 Fig. 6, a side elevation of the completed body with an ear wire attached.

In constructing the body a rod 8 is placed

loosely in a tube 10 of precious metal or plate, with the ends of the rods projecting as shown in Fig. 1. The opposite ends of 55 the parts are successively compressed or reduced in a reducing machine of any usual construction. This operation swages the shell or tube, at and adjacent its end portions, as at 12, into tight and immovable engagement with the rod, at the same time 60 elongating and tapering the tube toward its ends. The portions of the rod 8 projecting beyond the shell are now cut off and the member appears as shown in Fig. 3. 65

The member 10 is next bent up on an arbor or otherwise into crescent shape as shown in Fig. 4. The ends of rod 8 are shortened by a drill or otherwise leaving cavities 13 and 14 in the ends of the body, 70 but leaving the wall of the body near its ends in tight or sealed contact with the rod, as at 16. This prevents all acids or other finishing liquids, in which the body is subsequently immersed, from access within the 75 body.

The body may be drilled to form perforations 18 to receive the pintle pin 19 of the ear wire 20 which enters the opening 14.

The body 10 is entirely seamless.

If preferred or if various cross sectional shapes of body are desired, the member after receiving the form shown in Fig. 4 is compressed in dies of the corresponding cross sectional contour.

We claim:

1. The method of forming the ornamental body of an earring consisting in inserting a rod loosely in a tube, next compressing the end portions of the tube upon the rod, then 90 bending the tube into the form of an incomplete ring, and finally in removing the extremities of the rod to form cavities in the ends of the tube.

2. The method of forming the ornamental 95 body of an earring consisting in inserting a rod loosely in a tube, next compressing the end portions of the tube upon the rod, and then bending the tube into the form of an incomplete ring.

3. The method of forming the ornamental body of an earring consisting in inclosing the intermediate portion of a rod in a non-contacting tube, next by compression im-

parting a double taper to the tube and forcing the ends thereof into contact with the rod, and finally bending the tube and rod into the form of an incomplete ring.

5 4. The method of forming the ornamental body of an earring consisting in loosely inserting into a tube a rod of greater length

than the tube, and next by compression elongating and tapering the tube until the ends of the tube are in contact with the rod.

In testimony whereof we have affixed our signatures.

ROBERT C. GIBBS.
JOSEPH ATKINSON.
